UNITED STATES PATENT OFFICE

162,654

POWER LAWN MOWER

Henry L. Heineke, Springfield, Ill.

Application January 16, 1951, Serial No. 13,831

Term of patent 14 years

(Cl. D40—1)

To all whom it may concern:

Be it known that I, Henry L. Heineke, a citizen of the United States, residing at Springfield, in the county of Sangamon and State of Illinois, have invented a new, original, and ornamental Design for a Power Lawn Mower, of which the following is a specification, reference being had to the accompanying drawing, forming a part thereof.

Fig. 1 is a side perspective view of a power lawn mower, showing my new design; and

Fig. 2 is a front perspective view thereof.

The characteristic features of the design reside in the portions shown in full lines.

I claim:

The ornamental design for a power lawn mower, substantially as shown and described.

HENRY L. HEINEKE.
